UNITED STATES PATENT OFFICE.

CHARLES A. GREEN AND HAROLD J. BRUNK, OF CHICAGO, ILLINOIS, ASSIGNEES TO THE C. F. PEASE COMPANY, OF CHICAGO, ILLINOIS, A CORPORATION OF ILLINOIS.

DRYING MACHINE.

Application filed January 11, 1923. Serial No. 611,940.

To all whom it may concern:

Be it known that we, CHARLES A. GREEN, a citizen of the United States, residing at Chicago, in the county of Cook and State of Illinois, and HAROLD J. BRUNK, a citizen of the United States, residing at Chicago, in the county of Cook and State of Illinois, have invented certain new and useful Improvements in Drying Machines, of which

10 the following is a specification.

This invention relates to improvements in drying machines and more particularly to blue print drying machines of the belt and drum type.

15 Some of the most troublesome factors encountered in the operation of this type of drying machine, as heretofore constructed, have been the unequal distribution of heat over the drying surface of the drum; the 20 sticking of the paper to the drum requiring the use of scrapers, or the like; the discoloring or spotting of the prints due to the action of entrapped steam generated at the point of entrance of the paper into the 25 machine, and the inability to maintain the drum at the proper temperature for varying working conditions.

According to the present invention all of these difficulties are overcome, the first mentioned two by the use of a drum constructed of copper, the third by inclining the forwardly moving feed run of the belt upwardly at a tangent to the drum so as to provide against the collection of water or 30 steam along the line of engagement between the belt and the drum and the pocketing of such steam between the latter and the paper, and the fourth by the provision of an automatically operable heat regulator associated with the drum for controlling the 35 temperature of the latter.

In the present improvements applicant decided upon a copper drum as distinguished from those of other metals such as 40 heretofore used, primarily to overcome the unevenness in heat distribution, which had been an objectionable feature of the prior machines. In actual use, however, not only was this feature overcome by the use of a 45 copper drum but in addition, and of even greater importance, it was discovered that the paper would not stick or adhere to such a drum, said paper standing free or clear of the same upon emerging from between 50 the latter and the belt. Thus the advance

in the art by the use of copper in the construction of the heating or drying drum is two-fold.

In addition to the objects and advantages of the invention appearing from the foregoing, many others will be apparent to those skilled in the art from a reading of the following specification taken in connection with the accompanying drawings wherein one form of the invention is illustrated.

In the drawings—

Figure 1 is a side elevation of a drying machine constructed in accordance with the present invention;

Fig. 2 is a front elevation thereof, certain parts being shown in section and others broken away;

Fig. 3 is a detail sectional view taken through the dryng drum showing the heat regulator operatively associated therewith; and

Fig. 4 is a detail sectional view of the heat regulator.

Referring more in detail to the drawings, 80 the machine comprises a frame 10 made up of side frame members or units 10^a and 10^b tied together in suitably spaced relation by means of transverse horizontally and diagonally disposed reinforcing members 10^c.

The heating or drying drum of the machine is shown at 11 mounted horizontally between the side frame members 10^a—10^b and being supported in such position by means of rollers 12 carried by each of the side frames and extending inwardly from the latter into the opposite open ends of the drum. Three of these rollers spaced equidistantly apart are shown carried by each side frame and these engage metal bands 13 95 of steel or the like carried interiorly of the drum immediately adjacent its opposite open ends. As previously pointed out, it is contemplated according to the present invention to construct the drying drum 11, except for the bands 13 thereof, entirely of copper preferably in the form of a seamless tube.

A gas burner 14 in the form of a perforated pipe extends through the drum 11 and is mounted at its opposite ends in the side frames. This burner pipe is capped at one end as at 15 and at its other end said pipe connects with the supply pipe 16, the latter having interposed therein a suitable mixing valve 17 and cutoff valve 18. The side 110

- frames overlie the open ends of the drum except for the openings 19 through which access may be had to the interior of the drum and to the burner.
- 5 Surrounding the drum 11 and suitably spaced therefrom are a plurality of horizontally disposed rollers 23, 24, 25, and 26, over which and the drum passes the conveying and driving belt 27. The roller 23 is mounted with the opposite ends of its shaft journaled in suitable bearing grooves 28 provided in the front edges of the side frame members. Roller 24 is removably journaled across the top edges of the side frames.
- 10 Roller 25 is journaled in the upper forked ends 29 of levers 30 pivoted at 31 on the inner sides of the frame members. The levers 30 may be adjusted on their pivots 31 to regulate or control the tension of the belt 27, these adjustments being effected through screw threaded rods 32, which engage loosely through openings 33 in the lower ends of the levers 30, nuts 34 and coiled springs 35, the latter being anchored at one end to the frame members and at their other ends being connected to the ends of the rods 32. Thus by turning nuts 34 in one direction or the other, the roller 25 may be moved to either increase or decrease the tension of the belt. The forward roller 26 is journaled at its opposite ends in blocks 36 slidably carried on rods 37 anchored at their forward ends in the side frames, as at 38 and at their rear ends to members 39, which are fixed to the sides frames at the rear of said blocks. Screw threaded rods 40 engage through these blocks 36 and extend substantially parallel to the rods 37, said rods 40 being journaled at their rear ends in members 39 and at their forward ends are provided with hand wheels 41 whereby the blocks 36 and hence roller 26 may be adjusted back and forth upon the rods 37, this arrangement also providing for adjusting and regulating the tension of the belt. With this arrangement it will also be observed that either end of the roller 26 may be adjusted independently of the other end thereof in order to keep the belt centrally disposed with relation to the drum and rollers and to prevent lateral creeping thereof. The blocks 36 each carry a forwardly projecting arm or bracket 42 to which are secured the opposite ends of a fixed transverse rod 43, the belt 27 in its travel over or around roller 26, passing between the latter and this rod 43.
- Reference numeral 44 designates the feed run of the belt and as previously described, is inclined upwardly at a tangent to the heating or drying drum. Immediately beneath the feed run of the belt and extending between the side frame members and attached thereto, there is positioned a fixed table 45, conveniently termed a "feeding table", said table providing a rigid and firm support for that portion of the belt upon which the prints are fed to the machine. This enables the operator to spread the prints evenly and smoothly on the belt without danger of wrinkling or otherwise injuring the same and represents a distinct improvement in the art in that heretofore the feed run of the belt has been unsupported from beneath and the pressure exerted upon the prints by the operator in applying or spreading the prints on the belt, invariably resulted in the prints being creased or wrinkled, or pockets formed therein, due to the fact that the belt would give at the point where the prints were applied.
- Carried by one of the side frames on a suitable bracket 46 is a motor 47, which at its outer end carries a suitable worm 48 which is in constant mesh with worm wheel 49 mounted on a horizontally disposed shaft 50, the outer end of which carries a bevel gear 51, which meshes with a bevel gear 52 carried by collar 53 loosely mounted on vertical shaft 54. The collar 53 at its upper end carries a gear wheel 55 provided on its upper surface with a plurality of upstanding studs 56. Keyed to shaft 54 and slideable thereon above the collar 53 and its gears 52 and 55 is a gear wheel 57 having studs 58 depending from its lower face and adapted for coaction with studs 56 carried by gear 55. Pivoted to the side frame member at 59 is a lever 60 by means of which the gear 56 may be raised or lowered upon the shaft 54 to effect the engagement or disengagement of the studs 56 and 58. A countershaft is shown at 61 having mounted thereon gear wheels 62 and 63. A keeper plate is shown at 64 provided with three apertures designed for coaction with the spring pressed keeper 65 carried by lever 60 for maintaining said lever in its various positions of adjustment. The shaft 54 at its upper end is provided with a bevel gear 66 in constant mesh with bevel gear 67, the latter being carried by the adjacent outer end of the shaft of roller 23.
- As will be observed from the foregoing upon operation of the motor 47, assuming the gears 55 and 57 to be in the position shown in Fig. 1 of the drawings with their studs in intermeshing engagement, shaft 54 will be driven direct at full speed through the train of gears previously described, gear wheels 62 and 63 merely idling in this relation of the parts. By lifting lever 60, however, and bringing gears 57 and 63 into mesh and incidentally disengaging the studs 56 and 58, the shaft 54 will be driven at half speed, the power in this case being transmitted to the gear 57 through the countershaft 61, as will be readily understood. In this position of the lever, the keeper 65 thereof will engage the uppermost aperture in the keeper plate 64. In full

speed driving relation the keeper 65 will engage the lowermost aperture in plate 64, the middle opening in said plate being engaged by the keeper when the parts are in 5 neutral position.

Thus the roller 23 is driven direct from the power source while the other rollers 24, 25 and 26 are idler rollers. In operation, the belt 27 and the drum, are, of course, 10 constantly driven while the parts are in driving relation, the direction of travel being indicated by the arrows in Fig. 1. After the prints to be dried have been washed, they are fed to the run 44 of the belt 27 over the rod 43, the table 45 affording a rigid and firm support for the belt at this point, thereby facilitating the feeding in of the prints. The prints, as soon as they are picked up by the belt 44, are conveyed forwardly in the 15 direction of the arrow to the drying drum 11, where they contact directly with the outer periphery of the latter and are held in such contact by the belt in the continued movement thereof, said prints in their travel 20 in contact with the drum being thoroughly dried and emerge in such state at the point 67 after having traveled in contact with the drum through the greater portion of a complete rotation thereof. The prints as they 25 emerge from the drum at the point 67, stand clear or free of the surface thereof and are caught or collected in a suitable tray 69, the latter being supported by arms 30 pivoted to the frame members so as to 35 permit of the tray being swung up on top of the frame members whenever desired. Feet 72 are provided on the arms 70 to provide a support for the tray when in its raised position so as to prevent contact or interference with the top roll 24. The arms 70 40 at their lower ends are provided with adjustable stops 73 designed for coaction with the front edges of the side frame members for properly positioning the tray with 45 relation to the drum, it being preferred, according to the present invention, to maintain the inner edge of the tray in rather close proximity to the periphery of the drum but always out of contact therewith, as it has 50 been found in practice that the corroding or oxidizing of the outer surface of the drum tends to enhance the desirable qualities thereof previously described. Should the tray contact with or scrape against the 55 drum this oxidizing process would be retarded.

As the prints are fed over rod 43 a substantial quantity of the water carried by said prints is squeezed therefrom, this water dripping into a suitable tray 74 positioned at the bottom of the machine immediately beneath said rod. The rod 43 is 60 stationary and in practice it has been found very effective in removing substantial quantities of water from the prints as the same

are fed into the machine. As previously pointed out, the upward inclining of the feed run of the belt is considered an important feature. As will be observed from the drawings, particularly Fig. 1, this provides for efficient draining of the water away from the drum at the point of entrance of the prints, thus preventing any accumulation at this point or the pocketing or entrapping of steam, such as would occur in the event of such accumulation. In prior machines, as previously pointed out, considerable difficulty has been encountered from the action of steam on the prints as the same are being dried, this steam action upon the chemical employed in the printing process, discoloring or spotting the prints, some times to a marked degree. It has been found in the use of the present improvements that this difficulty is entirely overcome owing to the disposition of the feed run of the belt relative to the drum. 70 75 80 85

Should repair or replacement of the belt ever become necessary in the present machine, the removal of the belt may be very quickly effected by merely releasing the tension thereon and lifting the roller 23 out of its bearing grooves or sockets 28. This is also an improvement over prior machines 90 wherein it has been necessary in removing any one of the rollers to withdraw the same lengthwise through one of the side frames. 95

An important feature of the present improvements resides in the provision of a heat regulator for controlling the temperature of the drying drum. This heat regulator is designated generally by reference character 20, the adjustable controlling or regulating element of which bears reference character 21 and is in the form of a calibrated dial, 100 or the like, as shown. The heat responsive unit of the regulator bears reference character 22 and extends through the adjacent side frame of the machine and to a substantial distance into the drying drum immediately adjacent but out of contact with the inner periphery thereof. In order to subject the heat responsive unit to the temperature of the wall of the drying drum as distinguished from the interior thereof, a suitable housing 75 of insulating material surrounds said unit, this housing extending completely through the drum and being supported at its opposite ends by brackets 76 or the like, attached to the side frames. 105 In this manner the heat responsive unit of the regulator is confined between the insulating housing and the inner periphery of the drum in such wise that said unit is influenced only by temperature changes in the 110 wall of said drum. 115 120 125

Referring more in detail to the construction of the heat regulator shown in the accompanying drawings, particularly Fig. 4 thereof, the calibrated dial or controlling

element 21 is mounted on the outer end of a screw threaded spindle C, which engages through an adjacent wall of the housing L. The upper end of a lever K is hooked or otherwise secured to the inner end of spindle C and depends therefrom downwardly through housing L to a point adjacent its lower end, said lever carrying at its lower end a plunger N, which latter is normally urged forwardly by the spring M towards its seat S with which it cooperates in regulating or controlling the flow of gas through the outlet orifice T. R designates the gas inlet which is attached to the main supply pipe by ordinary union Q. Mounted in one wall of the housing L slightly below the upper end of lever K and extending outwardly from said housing a substantial distance is a metal tube G of material such as copper, having a high coefficient of expansion. This tube is closed at its outer end and contains a rod H of material such as porcelain having a low coefficient of expansion, this rod being supported centrally within the tube G by means of asbestos cushions I, or the like and impelled toward said closed end by spring F. Held in contact with the inner end of rod H is an extension rod E, also of porcelain, which, at its outer end projects from tube G and into contact with lever K. The heat responsive unit comprised, as just described, of copper tube G and porcelain rods H and E, extends through the adjacent side frame of the machine and into the drying drum, as previously described. In operation, as the drum heats up the copper tube G expands, causing end of extension rod E to recede, resulting in the lower end of lever K being moved to the right by plunger spring M, causing the plunger N to reduce or regulate the flow of gas, so as to maintain the temperature of the drum within the limits desired and as indicated by the calibrations on the adjustable dial 21. One edge of the dial 21 is serrated and a pivoted indicator coacting with said serrations is employed for maintaining the dial in its various positions of adjustment. Adjustment of dial 21, as will be observed, moves the inner end of a spindle C to the right or left to vary the heat control of the regulator, as will be readily understood by those skilled in the art.

15 The use of a heat regulator for controlling the temperature of the drying drum and for maintaining the same within certain prescribed limits for varying working conditions is an important improvement in the art for the reason that it prevents to a large extent burning or carbonizing of the belt, a source of considerable annoyance and expense in drying machines as heretofore constructed. During the use of such prior drying machines the drying drum, during cer-

tain periods in the use of the machine, heats up to a considerable degree, resulting in a carbonizing of the belt and subsequent rapid deterioration thereof, necessitating replacement. Carbonizing or burning of the belt may also result upon the shutting down of the machine but this is prevented in the present improvements by the use of a sheet of asbestos, shown in dotted lines at 77 in Fig. 1, or other suitable insulating material, which is fed in between the drying drum and the belt, when the machine is shut down so as to protect the belt from over-heating.

The construction of the heat regulator per se herein illustrated and described forms no part of the present improvements, claims herein, in so far as this feature is concerned, being restricted to the use of a heat regulator in a drying machine of the character described. Obviously therefore it is not desired to limit or in any wise restrict the claims to the particular form of heat regulator shown. It will also be obvious to those skilled in the art that the improvements are susceptible of various changes and modifications without departing from the spirit of the invention and accordingly it is not desired to limit or restrict the same, except where limitations appear in the appended claims.

What we claim is—

1. In a machine of the class described, a drying drum, a belt in engagement therewith, the feed run of the belt traveling upwardly at a tangent to said drum, and a supporting element underlying said run.

2. In a drying machine, a drum, means for heating the same, a plurality of rollers, a belt passing over said rollers and around said drum, means for driving one of said rollers, and means for adjusting a plurality of said rollers to control the travel and tension of said belt.

3. In a drying machine, a drum, means for heating the same, a plurality of rollers, a belt passing over said rollers and around said drum, means for driving one of said rollers, said belt in passing from one of said rollers to the drum traveling in an upwardly inclined plane tangentially thereto, thereby providing for drainage away from the drum along the line of initial engagement between the latter and the belt, and a feed table underlying said inclined portion of the belt.

4. In a drying machine, side frame members, a drum rotatably mounted therebetween, means for heating the same, a plurality of rollers, a belt passing over said rollers and around said drum, and means for driving one of said rollers, the latter being removably journaled in said frame members.

5. In a drying machine, a drum, means for heating the same, a plurality of rollers, a

- belt passing over said rollers and around said drum, means for driving one of said rollers, the belt in passing from one of said rollers to the drum traveling in an upwardly inclined plane tangentially thereto, thereby providing for drainage away from the drum along the line of initial engagement between the latter and the belt, said belt passing around the major portion of said drum and providing a discharge above said inclined portion of the belt, receiving means at said discharge, said receiving means being in the form of a tray, and means for adjusting the latter with respect to said drum.
6. In a drying machine, a drum, means for heating the same, a plurality of rollers, a belt passing over the latter and around said drum, one of said rollers being mounted below and forwardly of said drum, the feed run of said belt extending from said last named roller to the drum along an upwardly inclined plane, and means for adjusting said roller.
7. In a drying machine, a drum, means for heating the same, a plurality of rollers, a belt passing over the latter and around said drum, one of said rollers being mounted below and forwardly of said drum, the feed run of said belt extending from said last named roller to the drum along an upwardly inclined plane, means for adjusting said roller, and a stationary rod associated with said roller over which the material to be dried is dragged in its passage to said belt.
8. In a drying machine, a drum, means for heating the same, a plurality of rollers, a belt passing over the latter and around said drum, one of said rollers being mounted below and forwardly of said drum, the feed run of said belt extending from said last named roller to the drum along an upwardly inclined plane, means for adjusting said roller, and a stationary rod associated with said roller over which the material to be dried is dragged in its passage to said belt, said rod being adjustable with said roller.
9. In a drying machine, side frame members, a drum rotatably mounted therebetween, means for heating the same, a plurality of rollers, a belt passing over the latter and around said drum, and means for driving one of said rollers, the latter being mounted in grooves in the edge of said frame members to permit of its removal laterally with respect to its longitudinal axis.
10. In a drying machine, frame members, a drum therebetween, and a plurality of rollers carried by said frame members and extending inwardly therefrom into the opposite ends of said drum, and rotatably supporting the latter by engagement with the inner periphery thereof.
11. In a machine of the class described, a drying drum, a belt in engagement there-
- with, guide rollers for said belt, the feed run of the belt extending upwardly at a tangent to said drum, and a rigid support extending beneath said belt and in contact therewith.
12. In a machine of the class described, a drying drum, a belt in engagement therewith, guide rollers for said belt, and a feeding table under the feed run of said belt for supporting the latter.
13. In a drying machine of the class described, the combination with the drying drum thereof and gas burner for said drum, of a heat regulator comprising a heat responsive unit and means actuated thereby for controlling the flow of gas to said burner, said heat responsive unit projecting into said drum in close proximity to the inner periphery thereof but out of contact therewith.
14. In a drying machine of the class described, the combination with the drying drum thereof and means for heating the same, of a heat regulator operable by the heat of said drum for controlling the temperature of said drum.
15. In a drying machine of the class described, the combination with the drying drum thereof and gas burner for said drum, of a heat regulator comprising a heat responsive unit and means actuated thereby for controlling the flow of gas to said burner, said heat responsive unit projecting into said drum in close proximity to the inner periphery thereof but out of contact therewith, and a housing for said unit positioned in such wise that said unit is influenced only by temperature changes in the wall of said drum.
16. In a drying machine of the class described, the combination with the drying drum thereof and means for heating the same, of a heat regulator operable by the heat of said drum for controlling the temperature of the latter, said heat regulator comprising a heat responsive element mounted adjacent the surface of said drum.
17. In a drying machine of the class described, the combination with the drying drum thereof, and means for heating the same, of a heat regulator operable by the heat of said drum for controlling the temperature of the latter, said heat regulator comprising a heat responsive element mounted adjacent the surface of said drum, and means for insulating said element from said heating means.
18. In a drying machine of the class described, a copper drying drum in the form of a seamless tube.
19. In a drying machine, a supporting frame work, a drying cylinder rotatably carried thereby, a belt in engagement therewith, guide rollers for said belt, and means whereby one of said rollers may be removed.

from said frame work laterally with respect to its longitudinal axis.

20. In a drying machine, a drum, means for heating the same, a plurality of rollers, a belt passing over the latter and around said drum, one of said rollers being mounted below and forwardly of said drum, the feed run of said belt extending from said last named roller upwardly and in an inclined plane to the drum, and means for adjusting said roller.

21. In a drying machine, a drum, means for heating the same, a plurality of rollers, a belt passing over the latter and around said drum, one of said rollers being mounted forwardly of said drum, the feed run of said belt extending from said last named roller to the drum, and a stationary rod adjacent said roller over which rod the material to be dried is dragged in its passage to said belt.

22. In a drying machine, a drum, means for heating the same, a plurality of rollers, a belt passing over the latter and around said drum, one of said rollers being mounted forwardly of said drum, the feed run of said belt extending from said last named roller to the drum, and a stationary rod adjacent said roller over which rod the material to be dried is dragged in its passage to said belt, said roller being adjustable.

23. In a drying machine, frame members, a drum therebetween, and a plurality of rollers carried by said frame members and extending inwardly therefrom into the opposite ends of said drum, and rotatably supporting the latter by engagement with the inner periphery thereof, said rollers being removably mounted on said frame members.

24. In a drying machine, a frame, a drum, and members carried by said frame and engaging the inner periphery of said drum for supporting the same.

25. In a drying machine of the class described, a copper drying drum in the form of a seamless tube having bands of wear resisting material at its opposite ends to serve as track members.

26. In a machine of the class described, a drying drum, a plurality of rollers, a belt passing over said rollers and around said drum, means for driving one of said rollers and means below the point at which said belt leaves said drum for receiving the material operated upon, said means being in the form of a tray adjustable with respect to said drum.

In testimony whereof, we have subscribed our names.

CHARLES A. GREEN.
HAROLD J. BRUNK.
